UNITED STATES PATENT OFFICE.

AVILA THOMAS, OF DETROIT, MICHIGAN, ASSIGNOR OF ONE-HALF TO
EUGENE F. GLOCK, OF DETROIT, MICHIGAN.

REINFORCED CONCRETE.

No. 827,892.

Specification of Letters Patent.

Patented Aug. 7, 1906.

Application filed December 19, 1904. Serial No. 237,380.

To all whom it may concern:

Be it known that I, AVILA THOMAS, a subject of the King of Great Britain, residing at Detroit, county of Wayne, State of Michigan, have invented a certain new and useful Improvement in Reinforced Concrete; and I declare the following to be a full, clear, and exact description of the invention, such as will enable others skilled in the art to which it pertains to make and use the same, reference being had to the accompanying drawings, which form a part of this specification.

This invention relates to reinforced concrete.

It has for its object an improved tie-bar and connected adjustable bonding device to be used generally in concrete structures.

In the drawings, Figure 1 is a perspective showing the movable bonding device. Fig. 2 is a plan view of a slotted blank from which the bonding device of Fig. 1 is formed. Fig. 3 shows a beam-and-floor construction in which the tie-bar and adjustable bonding device of Fig. 1 is employed. Fig. 4 is a cross-section of a vertical-column structure. Fig. 5 is a vertical section from corner to corner of the same column. Fig. 6 shows the tie-bar and bond applied to wall construction and employed to tie together the tile employed to construct the wall. Fig. 7 shows the tie applied in the construction of a flue or a chimney. Fig. 8 shows a blank for a bond-iron in which the spreading members are all arranged at one end of the body or eye part.

The bonding device consists of a piece of metal 1 split by longitudinal slits into a number of parts which project from a body or eye part 2. The body part is cut by short slits 3 and 4 into three portions. The middle portion 5 is bent to a semicircle in one direction, and the side portions 6 and 7 are bent with a semicircular curve in the other direction, forming an opening bounded by inclosing sides or part-circumferential zones through which a rod or bar 8 may engage. The several arms 9 10 11 12 are spread in whatever direction may be desirable for the work with which the bond is to be subsequently used. In use these bond-irons are strung on a rod and are spaced along the rod in accordance with the requirements of the particular work. Where extraordinary strength is required, they are placed close together. Where great strength is not required, they may be

placed at a greater distance apart. The 55 arms 9 and 10 and 11 and 12 are preferably given a quarter-twist or a partial twist and are bent to angle with the axis of the rod upon which the bonds are to be strung in order that the shearing stress of the strengthened structure may come as nearly as possible at a right angle to the general direction of these arms. For example, the shearing stress of the beam 15, (shown in Fig. 3) may be supposed to be along the line 18 19 on the one 65 side of the middle point of the beam and on the other side of the middle point of the beam on the lines 16 17, and the arms 9 and 10 and 11 and 12 are arranged to lie across and as nearly as practicable perpendicular to 70 the line of this stress.

On the one side of the center in the construction of a beam similar to the beam 15 (shown in Fig. 3) only one full double-ended bond-iron need be used at the middle point 75 and half bond-irons at each side. In the construction of the floor 20 above the beam 15 tie-rods 21, with bond-irons 22 strung thereon, are placed transverse to the course of the tie-rod 8. In the construction of a 80 column (shown in Figs. 4 and 5) the bond-irons similar to those above described are strung on rods which extend lengthwise the column, and the spreading parts of the bond-irons are bent inward toward the center of 85 the column and spread upward and downward. For a rectangular column, such as that shown in Fig. 4, the four tie-rods 31, 32, 33, and 34 are assembled at the corners of a 90 square and inside the mold in which the column is to be constructed. The bond-irons are properly strung along the tie-rods, and the mold is thereafter filled with the plastic concrete, which hardens and produces a reinforced column of great strength. 95

In wall construction, such as is indicated in Fig. 6, the building-tiles 410 and 420 are made with the bond-irons 430 and 440 inserted in the tile, with the ends 91 and 92 projecting from that face of the tile which is to lie toward the interior of the wall. Preferably the tile is made with ribs 81 and 82, that engage against corresponding ribs 83 and 84 of the opposing tile, and the inward-projecting ends of the bond-irons project between the ribs 81 and 82, so that in the assembled structure there is formed a flue across which the inward-projecting ends of the bond-irons 100 105

extend. The body part or stringing part of the bond-iron lies external to the body of the tile, but on that side of it which is to lie toward the interior of the wall, and the tile are 5 assembled and the tie-rods 71 and 72 strung through the eyes of the bond-irons, after which the flue-opening is filled with cement. With this structure the crushing weight of the wall may be sustained to a very large extent by the tie-rods.

In chimney or flue structures, such as that shown in Fig. 7, a similar process of construction is carried out. The tile-pieces 51 and 52 are constructed with one branch of 15 the bond-iron inserted in the tile, with one branch extending out from the tile and in a direction to meet and overlap the corresponding arm from the oppositely-placed tile. The eyes 43 and 44 and 45 and 46 are on 20 the inside face of the tile and are left free to enable the tile to be strung on the rods 47, 48, 49, and 50.

The flue is completed by filling in with 25 plastic material that part of the wall structure of the flue which covers the lapping ends 41 and 311 of the bonding device.

The forms of wall construction and column construction shown are shown as examples of the manner of using the combined 30 tie-rod and bonding device which forms the subject of this invention. It is apparent that the spreading or bending of the arms 9 10 11 12 should correspond with the work with which the bond is to be used and 35 that the special form shown in the illustrations accompanying this specification only illustrate a few of the many forms to which they may be bent. It is also obvious that the invention is not to be confined to a bond- 40 iron with four branches or with six branches or any specific number of branches, but that the essential features of the invention are comprised in a bond-iron adjustable on or that can be arranged along a tie-rod either 45 close together or in scattered relation, as may be desired or required.

It is also obvious that at times it may be desirable to use a single-ended bond-iron, such as is shown in Fig. 8, formed by bending 50 the parts *d e f* to form the eye and spreading the parts *a b c*.

What I claim is—

1. A metallic bond for concrete reinforcement comprising a relatively flat metallic strip constituting a body portion, the same being provided with a loop intermediate the edges of the strip, a tie-rod in said loop, and an arm extending from said body portion.

2. A metallic bond for concrete reinforcement comprising a relatively flat metallic strip constituting a body portion, the same being provided with a loop intermediate its

edges, a tie-rod in said loop, and said strip being slotted and bent to form arms radiating from said body portion at an angle thereto 65 and to the tie-rod.

3. In a concrete beam structure, the combination with an enveloping mass, of a cementitious nature, of a tension and compression resisting bar and a bond-piece engaging 70 about the same intermediate its length, the bond comprising a body portion having intermediate its edges a loop through which passes the said bar, and a plurality of arms radiating from said body portion at an angle 75 thereto and lying transversely of the line of the strain on the structure.

4. A unitary bond for concrete reinforcement comprising a sheet-metal blank having its body portion slit longitudinally and the 80 parts thus separated bent away from one another, and arms radiating therefrom and bent at an angle to said body portion, substantially as described.

5. As a new article of manufacture, a 85 sheet-metal bond for concrete reinforcement comprising a blank having its middle portion slit longitudinally and the parts thus separated bent away from one another, and its end portions slit longitudinally and bent at 90 an angle to the middle portion; substantially as described.

6. Means for concrete reinforcement, comprising a blank pierced with a plurality of series of slits and with the alternate portions of 95 metal separated by the slits of one series bent in opposite directions, and with the arms separated from one another by the other series of slits bent at an angle to the portion traversed by the first-named series of slits, 100 substantially as described.

7. In a concrete beam structure, the combination with an enveloping mass of a cementitious nature, a unitary bond therefor comprising a sheet-metal blank having its 105 body portion slit longitudinally and the parts thus separated bent away from one another, arms radiating therefrom and bent at an angle to said body portion, and a tension and compression resisting bar having connection 110 with said body portion of the bond.

8. Means for reinforcing concrete comprising a tie-rod and a bond-piece carried thereby, the same comprising a body portion having means for engaging the tie-rod and 115 being slotted and bent beyond said engaging portion to form oppositely-disposed arms radiating therefrom.

In testimony whereof I sign this specification in the presence of two witnesses.

AVILA THOMAS.
